UNITED STATES PATENT OFFICE.

THEODORE A. SCHLAEBITZ, OF LINCOLN, NEBRASKA.

DESIGN FOR A WIND-WHEEL.

SPECIFICATION forming part of Design No. 29,710, dated November 22, 1898.

Application filed October 15, 1898. Serial No. 693,670. Term of patent 7 years.

To all whom it may concern:

Be it known that I, THEODORE A. SCHLAEBITZ, a citizen of the United States, residing in Lincoln, county of Lancaster, and State of Nebraska, have invented and produced a new and original Design for a Wind-Wheel, of which the following is a specification, reference being had to the accompanying drawing, in which the figure represents a perspective view of the design.

The leading or material feature of my design, as shown, is a vertical pyramid 1, and a minor feature is the globe or sphere 2, which surmounts said pyramid, as shown. The base 5 of the pyramid is a circular disk 3, and below

the latter is arranged another disk 4, of larger diameter, and intermediately of the two disks is a series of funnel-shaped devices 5. Above the ball or sphere 2 is the figure of a cock 6, and between the latter and sphere 2 is a 20 weather-vane of ornamental shapes.

Having described my invention, what I claim as new is—

The design for a wind-wheel, as shown and described.

THEODORE A. SCHLAEBITZ.
